UNITED STATES PATENT OFFICE

MICHAEL KIWAD, OF NEW YORK, N. Y., ASSIGNOR TO LA BELLE SPECIALTY CO., INC.,
A CORPORATION OF NEW YORK

DESIGN FOR A BASE FOR CLOCKS, LAMPS, OR ARTICLES OF ANALOGOUS NATURE

Application filed March 26, 1931. Serial No. 39,256. Term of patent 3½ years.

To all whom it may concern:

Be it known that I, MICHAEL KIWAD, a citizen of the United States of America, and a resident of the city of New York, county of Bronx, and State of New York, have invented a new, original, and ornamental Design for a Base for Clocks, Lamps, or Articles of Analogous Nature, of which the following is a specification, reference being had to the accompanying drawing, forming a part hereof.

In the drawings:

Figure 1 is a front elevational view of the base for clocks, lamps, or articles of analogous nature, the rear view being the same as the front except the figure which is viewed from behind; and

Figure 2 is a top plan view of the same.

I claim:

The ornamental design for a base for clocks, lamps, or articles of analogous nature substantially as shown and described.

MICHAEL KIWAD.
